PUMP FEED OIL EJECTOR CAN

Reinhold Langguth, Kapellen, Kreis Moers, Germany

Application May 20, 1953, Serial No. 356,247

Claims priority, application Germany October 10, 1952

9 Claims. (Cl. 222—255)

The invention relates to oil ejector cans, in which, by means of a pump, oil is pressed out of the container through an ejection spout carried by a screw-cap or the like. For a withdrawal as complete as possible of the oil contents from the container, the inlet opening of the suction pipe of the pump is generally extended downwards to near the bottom or, in an angularly projecting form, down to the inside corner formed by the bottom and the shell of the can.

It has already been suggested to provide for a pivotal arrangement of the angularly projecting end of the suction pipe round the middle axis of the container in such a way as to secure its automatical adjustment to the lowest spot each time the can is held in an upwardly inclined position.

In the case of all these pump arrangements, it has not been taken into consideration that the ordinary working position of most oilers, in particular of such of simpler design, is the vertical or inclined one, and that the pump is not working, when the said oil ejector cans are held in a downwardly inclined position, because the inlet opening is raised above the oil level.

In order to avoid this disadvantage, the pump, according to the invention, has a delivery chamber separated from the ejection spout by means of a delivery valve, the delivery chamber being provided, immediately below the screw-cap of the can, with inlet openings that can be closed. When the can is tilted downwards, the oil enters the delivery chamber through these openings and will be delivered through the ejection spout at each stroke of the pump, the openings closing at the same time.

The inlet openings of such "cover pumps" may also be designed as suction valves known from the "bottom pumps." Preferably, however, an arrangement is used in which, according to the invention, the delivery chamber communicating with the ejection spout by means of a delivery valve, is tightly closed at its other end by a tube sliding therein and moved by the lifting lever, the tube being closed at its free end and being provided with inlet openings, which are lying open towards the interior of the container, when the pump is at its neutral position, and which are closed at the beginning of the lifting movement, when the tube enters the surrounding guide-way. The latter arrangement has the advantage of greater simplicity and reliability above the use of a suction valve, as the entering of the oil into the inlet openings is considerably more favoured by the vacuum developing in the delivery chamber during the delivery stroke than by the use of suction valves.

By means of an oil ejector can provided with such a cover pump, most of the lubrication openings at machines and the like, inclusive of such ones having a very low position, can be provided with oil, when the oiler is held in a vertically downward or downwardly inclined position. Excepted are only lubrication openings, for the serving of which the oiler cannot be held in a downwardly inclined position on account of an unfavourable ar-

2

rangement of other machine parts or too high a position of the lubrication openings.

Another feature of the invention is, therefore, to provide the pump oiler, in addition to the cover pump also with the bottom pump. This measure is completed by the additional bottom pump being provided with a suction tube pivotally arranged round the middle axis of the container, the suction tube adjusting itself automatically to the respective lowest spot of the container, when the can is held either in an upright or inclined position as the case may be. On account of this feature it does not matter, in which position the can is held with regard to its inclination, since, in the case of this preferred form, the oil ejection can is working from out any position.

Further features of the invention will be apparent from the following description of one preferred form of the invention, this form being an oil ejector can provided with a cover pump and with an additional bottom pump.

20 The drawing shows a vertical sectional view centrally through the oil ejector can.

The bottle-like oil container 1 of the oil ejector can is closed, at its upper end, by a screw-threaded cap 2, a packing ring 3 being inserted between the can body 25 and the cap. A downwardly extending tube 5 is screwed, in a well-known manner, into a threaded bore-hole 4 located centrally in the cap, the tube being provided, at its upper end, with a flange 6, the central opening of which is closed by a ball 8 held in position by a spring 7. A vertically movable suction tube 9 is slidably mounted on the rigidly fixed tube 5, the lower end of the suction tube 9 being rigidly connected with a branch rod 11 embracing a draw-bar 12, to which it can be tightly screwed by means of a cap nut 13 or the like. Draw-bar 12 extends upwards through a bore-hole 14 in the cap and engages with its hook-shaped upper end 15 over the bridge 16 formed by a lifting lever 17, which can be moved in the direction of the arrow 18 by means of the hand embracing the can.

30 40 Underneath the branch rod 11, an angularly projecting pipe 19 is mounted easily pivoting the downwardly extending prolongation member 21 of the tube 9 and secured against sliding downwards by a spring ring 23 inserted in the grooves 22.

45 A cap 24 with opening 25 is screwed into the end of the pipe 19 projecting angularly to the inside corner of the container. Generally, the opening 25 is closed by a ball 26 controlled by a spring 27. At an upwardly inclined position of the can, this pivotally mounted suction pipe 19 with its suction valve 25 and 26 will always adjust itself, in consequence of its own weight, to the lowest spot of the can interior.

50 55 Above the delivery valve 6, 8, there is an antechamber 28 for the arrangement of spring 7, which is to keep the ball 8 in position. The antechamber passes over through a vertical borehole 29 and a transversal bore-hole 31 into another chamber 32, which is connected with the ejector spout 33. The chambers and boreholes 28 to 32 are arranged within a piece of light metal 34 which is mounted on cap 2 and preferably forms one single light metal casting with the latter.

60 65 Parallel with antechamber 28, a borehole 35 is provided for, serving as a delivery chamber for the cover pump. At its upper end, the delivery chamber 35 is closed by a ball 36 controlled and kept in a closing position by the spring 37 mounted in chamber 32.

Opposite this delivery valve 36, 37, a tightening, but movable shell 38 has been provided for in the delivery chamber 35 with its hollow space ending directly underneath the lower cap face 39 and with several inlet openings 41 for the oil at that level. At the neutral position of the shell as shown in the drawing, the openings 41

connect the delivery chamber 35 with the interior of the container. The shell is extending downwards as a solid body having, at its lower end, a circular groove 42 engaging the fork-end 43 of a cross arm 44 fixed to the upper end of the suction pipe 9.

A protection tube 45 is screwed into the screw-threaded cap 2 from below and coaxially with the drawbar 12, a packing ring 40 being inserted between the tube 45 and the cap 2. The protection tube surrounds the drawbar very tightly, as it is its task to prevent the oil from flowing off through the borehole 14, when the can is held in a downwardly inclined position. Underneath the protection tube 45 and in a well-known manner, a spacing tube with adjusting nuts may be fixed on draw-bar 12 for adjusting the stroke of all the movable parts of the pump. The transversal bore-hole 31 is closed by a threaded bolt 46, which allows the access also to the bore-holes 29, 31 and to chamber 32, in case of the passages being blocked, etc.

Inside of the pressure tube 5 and the suction tube 9, a long helical spring 47 is provided for, which tends to move down to the lowest position of the suction tube with all the parts fixed thereto.

The oil ejector can as described is operated as follows: On the lifting lever 17 being pressed down in the direction of the arrow 18, the drawbar 12 is lifted up and, by means of the cross arm 11, carries up with it the suction tube 9 and the pivotally mounted suction pipe end 19. By means of the cross arm 44, the shell 38 is carried upwards at the same time. As soon as the lifting lever is released, the parts will automatically be removed by spring 47 into the neutral position as shown.

In case the oil ejector can is held in a vertical or upwardly inclined position, the suction valve 25, 26 is surrounded by oil, which is sucked through the suction valve 25, 26 into the interior of the suction tube, when the latter 9, 19 is returning into the lowest neutral position. After a few strokes of the pump, the suction tube is filled with oil. At a subsequent uplift, the oil will be pressed through the delivery valve 6, 8 and the connecting chambers and holes 28, 29, 31, and 32 into the ejection spout 33. In consequence of the angular projection of the suction pipe, the oil contents of the container will be withdrawn completely (apart from very small remainders), and the pivotal mounting of the suction pipe 19 has the effect that, with the oil ejector can being held in an inclined position, the position of the plane passing through the central axis of the can, the lifting lever, and the ejection spout as compared to the respective inclination of the can does not matter at all, as the suction valve 25, 26 will always adjust itself to the lowest spot in the container.

At the handling of the ejector can as described above, the cover pump represented by the delivery valve 36, 37, delivery chamber 35, and by the shell 38 will have no effect whatever on the oil-quantity ejected. It is true that the shell 38 is carried along upwards, but no oil has entered through the inlet openings 41, as the oil level is farther beneath these openings, so that only the air is compressed in the delivery chamber, when the shell 38 is lifted upwards. If, in consequence thereof, the delivery valve 36 is opened against the action of the spring 37, the only effect is that some air enters the chamber 32. But this air will not hamper the oil passage of the bottom pump. On the contrary, it will support it, as the pressure effect of this air has a suction effect on the transversal borehole 31.

If the oil ejector can is held in a vertically downwardly inclined position for lubrication purposes, the cover pump will come into action instead of the bottom pump. When the shell 38 is in a neutral position, i. e. when the lifting lever 17 is not pressed down, the inlet openings 41 are lying open directly underneath the lower face of the cap 39, so that the oil can freely enter and more or less fill the delivery chamber 35.

If now the lifting lever 17 is moved in the direction of the arrow 18, the shell 38 is slid into the delivery chamber 35. At the beginning of this movement, the inlet openings are laterally covered by the guide-faces of the cap 2, so that the oil can no more leave through the inlet openings. Instead, the pressure produced will open the delivery valve 36, 37, and the oil is ejected through the ejection spout 33 on the lubrication place. With the lifting lever 17 returning into its neutral position as shown, the shell 38 moves again in the direction to the bottom of the can. In consequence thereof a vacuum is produced in the delivery chamber 35, causing the delivery valve 36, 37 being kept closed. The vacuum increases in the delivery chamber until the moment, when the inlet openings leave the lower cap-face, where they will be surrounded by oil. In consequence of the prevailing vacuum, the flow of the oil into the openings 41 is very strong, so that the delivery chamber is quickly and completely filled with oil. There is, of course, the possibility to replace the simple openings 41, which are covered at the beginning of the lifting movement, by a suction valve in conformity with the suction valve 25, 26. But it is quite obvious that such a safe and quick filling of the delivery chamber as obtained by means of the openings 41 cannot be reached by a suction valve, because, at the use of a suction valve, the vacuum is gradually compensated already before the final state is reached.

What I claim, is:

1. A feed oil ejector can of the class described, a cover cap at the upper end of the container, an ejection spout secured to said cap, a delivery chamber, a delivery valve between said delivery chamber and said ejection spout adapted to be opened towards the ejection spout by a pressure in the delivery chamber, a shell shiftable in said delivery chamber being closed at its end projecting into the container, inlet openings in said shell near its end, a spring influenced lifting lever pivoted on said cover cap, and connecting means between said shell and said lifting lever, whereby upon holding the can downwardly inclined oil being enabled to freely enter said delivery chamber and upon depressing said lifting lever said shell being moved into said delivery chamber thereby closing said inlet openings and pressing the oil through said valve and ejection spout whereas upon returning the lifting lever a vacuum will be produced in the delivery chamber favouring the refilling of the delivery chamber with oil.

2. In a feed oil ejector can with a cover pump according to claim 1, a bottom pump having an inlet opening arranged near the bottom of the container, and connections between said lifting lever and said bottom pump, whereby the oil of the container being fed into and out of the ejection spout when the can is being held upwardly.

3. In a feed oil ejector can with a cover pump according to claim 1, and a bottom pump having an inlet opening arranged near the bottom of the container, and a delivery valve, the delivery valve of the cover pump being arranged in the direction of the ejection spout, whereas the delivery valve for the bottom pump being arranged laterally thereto, an antechamber provided above the delivery valve for the bottom pump, and a transversal connection between said antechamber and the outer side of the delivery valve for the cover pump, said antechamber and said transversal connection, connecting the ejection spout with the delivery valve of the bottom pump.

4. In a feed oil ejector can with a cover pump according to claim 1, said connecting means between said lifting lever and said shell comprising, a draw bar passing through said cap, a protecting tube fixed with tightening effect in the cover cap and surrounding said draw bar whereby the oil being prevented from seeping through the cap along said draw bar.

5. In a feed oil ejector with a cover pump according to claim 1, a bottom pump having an inlet opening arranged near the bottom of the container, and a sliding

suction tube, said shell being connected for up and down movement with said lifting lever via said sliding suction tube.

6. In a feed oil ejector with a cover pump according to claim 1, said connecting means between said lifting lever and said shell comprising a draw bar passing through said cap, a bottom pump having an inlet opening arranged near the bottom of the container, a slidable suction tube, a circumferential groove, at the free end of said shell, a cross-arm rigidly fixed to the upper end of the suction tube and engaging said circumferential groove of the shell, and a second cross-arm fixed to the lower ends of said suction tube and said draw bar.

7. In a feed oil ejector can with a cover pump according to claim 1, and a slidable suction tube coaxially arranged in the container and consisting of two parts, the lower of which being directed toward the bottom corner of the container and being pivotally arranged round the upper part in order to adjust itself by the effect of its own weight to the lowest spot of the interior of the container, when the latter is held in an upwardly inclined position.

8. In a feed oil ejector can with a cover pump according to claim 1, and a slidable suction tube coaxially arranged in the container and consisting of two parts, the lower of which being directed towards the bottom corner of the container, a lifting lever pivoted on said cover cap, a draw bar passing through said cover cap,

10

15

20

25

a prolongation fixed at the upper part of the suction tube and turnably bearing the under part, said prolongation being secured to said draw bar, and a spring ring connecting said prolongation with said lower part of the suction tube.

9. In a feed oil ejector can with a cover pump according to claim 1, and a delivery valve, the delivery valve of the cover pump being arranged in the direction of the ejection spout, whereas the delivery valve for the bottom pump being arranged laterally thereto, an antechamber provided above the delivery valve for the bottom pump, and a transversal connection between said antechamber and the outer side of the delivery valve for the cover pump, said delivery valves, delivery chamber, antechamber and connection being arranged in one and the same body carrying the ejection spout and forming a single casting together with the cover cap.
